UNITED STATES PATENT OFFICE.

JEAN V. GIESLER, OF KNOXVILLE, TENNESSEE, ASSIGNOR TO THE FULTON COMPANY, OF KNOXVILLE, TENNESSEE, A CORPORATION OF MAINE.

DAMPER REGULATOR.

Application filed August 7, 1925. Serial No. 48,895.

This invention relates to a regulator, and more particularly to a thermosensitive damper regulator of the type disclosed in the patent to Weston M. Fulton, No. 5 1,153,214, dated September 14, 1915.

An object of the present invention is to provide a regulator of the above type which embodies the advantages of the former device and which possesses additional advantages in construction, mode of operation, and economy of manufacture.

More particularly, one of the objects of the present invention is to provide novel means for housing the thermosensitive bulb.

15 Another object is to provide a device of this type wherein the filling opening for introducing the thermosensitive liquid into the apparatus is positioned in one end of the guide rod, the plunger being used as a 20 cap for said opening.

Another object is to provide a regulator wherein the thermosensitive bulb extends through the frame into direct engagement with the bellows.

25 Another object is to provide a device of this type with novel means for working the bellows.

The above and other objects will be fully set forth hereinafter.

30 One form which the inventive idea may assume is shown in the accompanying drawings, which drawings, however, are for the purpose of illustration only and are not to be taken as defining the limits of the invention, reference being had to the appended claims for this purpose.

In the drawings, wherein like reference characters refer to like parts throughout the several views,

40 Fig. 1 is a side elevation of the apparatus constituting the subject matter of the present invention;

Fig. 2 is a view, partly in section, taken on the line 2—2 of Fig. 1; and

45 Fig. 3 is an enlarged sectional view taken on the line 3—3 of Fig. 2.

In the form shown, the apparatus comprises a frame or base 1 which is provided with an inner tubular portion 1^a (Fig. 3), 50 that is preferably exteriorly screw-threaded whereby the frame may be threaded into the wall of a receptacle, an outer tubular portion 1^b, and an intermediate portion constituted by a flange 1^c which is preferably

55 polygonal in outline. An opening 1^d extends longitudinally through the frame 1, and intermediate the ends of this opening the inner wall of opening 1^d of the frame is provided with an annular groove 1^e. Extending through the opening 1^d is a tubular bulb 2 of any suitable construction provided on its outer end with a flanged portion 2^a, for engagement with the portion 1^b of the frame 1, and intermediate its ends said bulb is beaded into the annular groove 60 1^e of the frame, as shown at 2^b. In order to insure that the bulb 2 will be securely held in place in the frame, the former may be secured to the lower end of the frame, as by means of soldering or brazing, as 65 at 3.

In engagement with the inner end of the bulb 2 and extending longitudinally and centrally therethrough, is a guide tube 4 which is provided with openings 4^a at the 75 inner end thereof for free communication between the tube and the bulb 2. Surrounding the guide tube 4, at a point adjacent the flanged portion 2^a of the bulb, is an annular supporting member 5 which rests on the upper surface of said flanged portion and is secured to the guide tube 4, as by means of solder 6.

An expandable and collapsible, corrugated vessel or bellows 7, of any suitable construction and material, is positioned immediately adjacent the frame 1 with the lower fold of the same extending around the annular supporting member 5, and the flanged portion 2^a of the bulb 2, said fold being secured to 80 these elements in any suitable manner, as by soldering. The member 5 thereby constitutes a stationary end wall for said bellows. The upper end of the guide tube 4 extends through the bellows 7 and is provided with 85 openings 4^b for establishing free communication between the tube and bellows.

90 Secured in any suitable manner to the movable end of the bellows 7, and resting in engagement with the upper end of the guide tube 4 when collapsed, is a rigid head 8 provided with an upwardly extending boss 8^a which is preferably exteriorly threaded and is provided with a suitable longitudinal opening 8^b therethrough. The portion of the head 8 immediately adjacent the lower end of this opening may be screw-threaded as at 8^c, and extending within the guide 95 100 105

tube 4, is a guide rod 9 provided at its outer end with a reduced threaded portion 9^a having engagement with the threaded portion 8^c of the head 8.

5 Guide rod 9 is provided at its upper end with a longitudinal opening 9^b in register with the opening 8^b of the head 8, and in communication with this longitudinal opening 9^b is a radial opening 9^c for establishing free communication with the interior of the guide tube 4 and bellows 7 for a purpose to be described hereinafter. A conically pointed or knife-edge plunger 10, which projects through a central opening 11^a in a cap 11, is threaded onto the upper end of the head 8 and constitutes a closure for the openings in the head 8 and rod 9. The cap 11, provided with lugs 12, is secured to the frame 1 in a manner to be described herein-
10 after. Registering openings are provided in the lugs 12 and through these openings extends a rod 13 (Fig. 2) constituting a pivot pin for a rocker 14, which latter is provided with a suitable recessed bearing
15 portion 14^a for engagement with the pointed or knife-edge end of plunger 10. A yoke 15 extends upwardly from the rocker 14 and receives a lever 16. Preferably, a threaded locking member 17 extends through the yoke
20 15 into engagement with the lever 16 to retain the latter in adjusted position relative to said yoke. Adjustable weights 18 of any suitable form are mounted on the lever and if desired the lever may be provided with
25 an opening 16^a whereby connecting means for the damper, or other member to be controlled, may be connected to the lever.

Novel means are provided for housing the bellows to protect the same, said means also 40 constituting a support for the cap 11. As shown, the base 1 is provided in the outer surface of the flanged portion 1^c thereof with an annular groove 1^f and a tubular member 19, constituting the housing, is positioned with its lower end extending into said groove. Preferably, the housing 19 is 45 constituted by seamless or brazed tubing, or a sheet of metal of the proper width is formed between rollers into tubular shape and employed for this purpose. Retaining members, such as screws 20, extend through openings in cap 11, through the housing 19 and into threaded engagement with the frame 1, whereby the cap 11 may be tightly 50 held against the upper edge of the tubular housing 19, and the latter is securely maintained in position.

The volatile liquid employed in the apparatus is introduced therein before the plunger 10 is threaded onto the boss of the head 8. For this purpose a fixture (which forms no part of the present invention and is well known in the art) having a three-way valve may be threaded onto the boss 8^a so that a suction may be applied through

passages 8^b and 9^b, 9^c to create a vacuum in the interior of the bellows 7 and bulb 2. Thereafter the three-way valve is turned to register with a container having the volatile liquid to be introduced, whereupon the liquid will flow into the instrument. Upon removal of the fixture the openings 9^b and 8^b are suitably closed as by means of a cork 21 and solder 22. The plunger 10 is then mounted on the boss 8^a and the tubular member or housing 19 is positioned on the base, the cap 11 engaged with the housing, and the screws 20 set up to retain the parts in operative position. The regulator is then suitably secured as by means of the threads 1^a on the body 1 to the wall of a container wherein the bulb 2 is subjected to a heating fluid. The heat of this fluid, which circulates around or is in heat interchanging relation with the bulb 2, produces vapor pressure on the liquid contained in said bulb and this pressure is transmitted to the movable end wall 8 through the liquid in said bulb and bellows, the liquid flowing through the opening 4^b to tube 4 and through the openings 4^b to the interior of the bellows 7. Variations of this pressure due to variations of temperature of the heating fluid result in movements of the head 8, which movements are transmitted by the plunger 10 to the rocker 14. Movement of the rocker about the pivot pin 13 results in movement of the lever 16 and consequently of the damper, or other member to be regulated, which is operatively connected to the lever. The lowering of the temperature of the heating fluid will decrease the pressure within the bulb 2 and bellows 7, whereby movement of the lever 16 in the opposite direction will take place.

It will thus be perceived that there is provided a damper regulator which is so constructed as to reduce the number of soldered joints required to a minimum and one where-
110 in the assemblage of the parts and introduction of the volatile liquid are readily carried out. The housing protects the bellows from injury and serves as a supporting member for the lever to be actuated. The bulb is attached directly to the bellows with the bulb extending through the frame into engagement with the end fold of the bellows whereby the latter is fixedly held in operative relation with the bulb.

115 While one form of the inventive idea has been described with considerable particularity, it is to be expressly understood that the invention is not limited thereto since changes may be made in the details of construction without departing from the invention defined in the following claims.

120 What is claimed is:—

1. A regulator comprising, in combination, a frame, a thermosensitive bulb and an 125 expandible and collapsible bellows secured 130

to said frame, a guide tube and guide rod associated with the ends of said bellows, said rod having a passage whereby a volatile fluid may be introduced into said bulb and bellows, and means actuated by the expansion and contraction of said bellows.

2. A regulator comprising, in combination, a frame having an opening therethrough, a thermosensitive bulb extending through the opening, said bulb having a bead and groove connection with the frame intermediate the ends of the latter, an expansible and collapsible bellows having an end fold thereof attached directly to the bulb, and means including a rocking member actuated by said bellows.

3. A regulator comprising, in combination, a frame having an opening therethrough, a bulb having a flanged end extending through the opening, the flanged end having engagement with the frame, an expansible and collapsible vessel having the end wall thereof attached directly to the bulb, and means including a rocking member actuated by said vessel.

4. A regulator comprising, in combination, a frame, a bulb and a bellows secured to the frame, a guide tube having openings therein mounted in the bulb and bellows, a guide rod secured to the bellows and extending into said tube, said rod having an opening therethrough for introducing a volatile fluid into the bulb and bellows, a plunger secured to the bellows and constituting a cap for said opening, and means including a rocker actuated by said plunger.

5. A regulator comprising, in combination, a frame, a thermosensitive bulb and an expansible and collapsible bellows secured to said frame, a filling opening in one end of said bellows, a plunger secured to said end of the bellows and constituting a cap for said opening, and means actuated by said plunger.

6. A device of the class described comprising, in combination, a frame having an opening therethrough, a bulb extending through said opening and supported by the frame, a tube extending into the bulb, a supporting member secured to the tube and having engagement with the bulb, a bellows secured at one end thereof to the said supporting member and bulb, a head secured to the other end of the bellows, a guide rod secured to said head and extending within said tube, and means having operative engagement with said head and motion transmitting means.

7. A device of the class described comprising, in combination, a frame having an opening therethrough, a tubular bulb having a bead extending into a groove in said frame and supported by the latter, a tube extending into said bulb, said tube having a plurality of openings in the wall thereof, a

supporting member secured to the tube and having engagement with the bulb, a bellows secured to said supporting member and bulb at one end thereof, a rigid head for said bellows having a threaded opening therein, 70 a guide rod threaded into said opening and extending in said tube, a plunger threaded onto the head and constituting a closure for the opening in the head, and motion transmitting means including a rocker having 75 engagement with said plunger.

8. A device of the class described comprising, in combination, a frame having a flanged portion intermediate the ends thereof and having an opening extending therethrough, a bulb extending through the opening and secured to the frame, a bellows secured to said bulb, a head for the bellows, motion transmitting means secured to said head, a housing for the bellows having the 85 inner edge thereof positioned in a groove formed in the outer surface of the flanged portion of the frame, a cap resting on the outer end of said housing, retaining means extending through said cap and flanged portion 90 within the housing for fixedly securing the latter in position, and means including a lever pivotally secured to the cap.

9. A damper regulator of the type wherein in a frame supports a rocking member that is actuated by an expansible and collapsible bellows associated with a thermosensitive bulb and guide tube is secured within the bellows characterized by the fact that the bulb is provided with a flange which is directly 100 connected to an end fold of the bellows and said guide tube acts as a stop to limit the contraction of the bellows.

10. A damper regulator of the type wherein in a frame supports a rocking member that is actuated by an expansible and collapsible vessel associated with a thermosensitive bulb, characterized by the fact that the frame is provided with a groove to receive a beaded portion of said bulb, and the bulb is 110 provided with a flanged portion directly connected to an end fold of said bellows.

11. A damper regulator of the type wherein in a frame supports a rocking member that is actuated by an expansible and collapsible bellows secured to a thermosensitive bulb and a rod is secured to the bellows for guiding the to and fro movements of the same, characterized by the fact that the rod is provided with a filling opening for introducing 115 a volatile fluid into the bellows and bulb.

12. A damper regulator of the type wherein in a frame supports a thermosensitive bulb that communicates with a collapsible bellows which is provided with a plunger for actuating rocking means and a rod is employed for guiding the to and fro movements of the bellows, characterized by the fact that the rod is provided with an opening 125 for introducing a volatile fluid into the 130

bulb and the plunger constitutes a cap for said opening.

13. A regulator comprising, in combination, a frame having means of connection to a container, a bulb secured in an opening in said frame, a bellows directly connected to said bulb, an apertured guide tube in said bulb and bellows, said bellows being

filled with a volatile liquid and said bulb containing said liquid and its vapor trapped ¹⁰ therein, a guide rod coacting with said tube, and motion transmitting means actuated by said bellows and mounted on said frame.

In testimony whereof I have signed this specification.

JEAN V. GIESLER.
